UNITED STATES PATENT OFFICE.

JOSEPH KRELL, OF BERLIN-PANKOW, GERMANY.

PRINTING MACHINE.

Application filed September 7, 1927, Serial No. 218,077, and in Germany September 21, 1926.

My invention relates to multiform printing presses of the type in which a sheet is printed on in successive positions, held in each position by stop fingers, and advanced from one position to another.

It is an object of my invention to improve a machine of this general type which has already been proposed, so as to perform various kinds of printing operations thereon.

10 To this end, I provide exchangeable means for operating the stop fingers.

In a preferred embodiment of my invention I provide stop fingers arranged in succession along the path through which the sheet is 15 advanced, and with each stop-finger unit I combine a set of cams, each cam being adapted to influence the stop fingers in a different manner, and I provide means for rotating the shaft and for displacing it axially so as to bring any cams out of each set to 20 bear on the finger units.

In this manner, the single-purpose machine referred to is changed into a universal machine which may perform various kinds of 25 work with a given combination of sets of cams, and may be changed for any kind of work by replacing a given combination by another.

In the accompanying drawings, machines embodying my invention are illustrated dia- 30 grammatically by way of example.

Figs. 1 to 11 illustrate a machine in which blanks may be printed once or twice, as desired, at the printing station,

Figs. 12 to 14 illustrate a machine in which 35 three printing operations are performed on each blank.

Fig. 1 is an elevation,

Fig. 2 a plan view of the single-printing machine,

40 Figs. 3 and 4 are sections, on a larger scale, on the lines III—III and IV—IV in Fig. 2,

Figs. 5 and 6 are sections similar to those in Figs. 3 and 4 but showing the parts in different positions,

45 Fig. 7 is a part elevation of a cam shaft for the machine by which the same blank is printed repeatedly.

Figs. 8 to 11 are diagrams illustrating the operation of the first-mentioned machine,

Figs. 12 to 13 are similar diagrams for the 50 second-mentioned machine.

Referring first to Figs. 1 to 11, 1 are the printing plates which are stored in a supply hopper 2, 3 is the frame of the machine, 4, 4 are guiding strips along which the plates are fed past the printing station, and delivered to a hopper 5, by automatic means, not shown, 6 is a printing arm, 7 is a printing pad on the arm, 27 is the driving shaft for the arm, the means by which said arm is operated 60 from the shaft forming no part of the invention and being not shown, 8' and 8'' are blanks moving toward the printing station where an inking ribbon may be provided so as to be forced onto the blank by the printing 65 pad, and to produce an impression on the blank through the medium of the printing plate, 10 is a supply of blanks, 9 is a suction elevator adapted to lift blanks from the supply 10 and to deliver them to the frame 3, 70 11, 11 are two endless conveyers extending along the frame 3 and moved along the machine as indicated by the arrows 12 in Fig. 1 in the same direction and at uniform velocity by means, not shown. The conveyers 75 engage the blanks which the elevator 9 deposits on them and carry them toward the printing station.

13 is a gear box arranged in front of, and 80 14, 15 are two gear boxes arranged at the rear of, the printing station at the left of the frame 3, 19, 20, and 21 are transverse shafts each extending from one of the gear boxes, 16, 17, and 18 are blank-retaining fingers arranged on each of the respective shafts, 25 is a cam 85 shaft extending through the three gear boxes 13, 14, and 15, and 26 is chain drive by which the cam shaft 25 is rotated at half the speed of the driving shaft 27.

A pair of cams, 22, 22', 23, 23', and 24, 90 24' is arranged on the cam shaft 25 in each of the gear boxes 13, 14, and 15, respectively, and each shaft 19, 20, and 21 is provided with an arm 19', 20', and 21', respectively, each arm being adapted to cooperate with each 95 pair of cams on the shaft 25. The shaft is splined and provided with a handle 37 at its front end for pulling it out. In the normal

position of the shaft the cams 22, 23, and 24 will cooperate with the arms on the transverse shafts, as shown for the gear box 13 in Figs. 4 and 6, while in its pulled-out position the 5 cams 22', 23', and 24' will cooperate with the respective arms.

Each shaft is provided with means for holding its arm engaged with the cam it is engaging at the time. Such means may be a 10 spring 36 at the end of an arm 36', as shown for the shaft 19 in Figs. 4 and 6. Each shaft is equipped with arms supporting rollers to engage the blanks from above and to hold them engaged with the belts or conveyers 15 11, 11 unless arrested by the fingers 16, 17, and 18. As will appear from Fig. 2, the shaft 19 has two arms 28 on either side of the finger 16 which extend in forward direction, each arm supporting a roller 29, and a single 20 rearwardly extending arm 30 with a roller 31. The shaft 20 has only a single roller 33 on a forwardly extending arm 32, and the shaft 21 has two rollers 35, also extending forwardly on two arms 34.

25 When the arms on the shafts 19, 20, 21 are in cooperation with the cams 22', 23', 24', which are depressed on one side only, as shown in end elevation for the cam 22' in Figs. 3 and 5, each blank will receive but 30 a single impression at the printing station, but, with the cams 22, 23, 24 in operation, which, as shown for the cam 22 in Figs. 3 and 5, have two depressions, each blank will receive two impressions.

35 Referring now to the diagrams Figs. 8 to 11, and assuming that the cams 22, 23, and 24 are in operative position so that each blank will receive two impressions, in Fig. 8 the printing arm 6 is elevated, and, at this moment, the arm 19' of the shaft 19 is engaged 40 with the concentric portion of the cam 22, as shown in Fig. 3. In this position of the arm 19', the finger 16 is lowered, as shown in dot-and-dash lines in Fig. 4, and projects 45 into the path of the first blank 8'' when it has been fed so far by the conveyers 11, 11. The preceding blank 8' is intercepted similarly by the finger 17, the arm 20' of the shaft 20 being also engaged with the concentric portion of its cam 23. The blank 8 preceding the blank 8', however, is free to move 50 out of the machine below the finger 18 which has been raised by its spring 36, the arm 21' engaging one of the depressions in the cam 24.

55 During the downward motion of the printing arm into its printing position as shown in Fig. 1, the fingers will remain in the positions of Fig. 8, and the blank 8' is printed, this being the first impression. While the 60 printing arm 6 is returning to its upper position, the finger 16 will still retain the blank 8'', as the cam shaft 25 performs one-half of a revolution, but the finger 17 is raised and the finger 18 descends, so that the 65 blank 8 is allowed to advance into position for the second impression in which it is retained by the finger 18, as shown in Fig. 9. While the blank remains in this position, the arm 6 descends for the second time, as shown in Fig. 10, and makes the second impression 70 on the blank 8''. Finally, all three fingers are raised as shown in Fig. 11, allowing the finished blank 8' to leave the machine, the blank 8'' to advance until it will be arrested by the finger 17 as in Fig. 8, and another 75 blank 8''' to advance as far as permitted by the finger 16 which will presently descend.

The arms supporting the rollers 29, 33, and 35 are keyed on their respective shafts so that 80 they will engage the blanks and hold them down on the belts 11, 11 only when the corresponding fingers are raised, but the arm of the roller 31 is freely supported on its shaft 19 so that it will bear on the blanks also when the finger 31 has been raised.

When the parts have returned into the position Fig. 8, the machine is ready to perform the first impression on the blank 8''.

By pulling the cam shaft 25 to the left in Fig. 1 by its handle 37 until the levers on the transverse shafts 19, 20, and 21 engage the cams 22', 23', and 24', each blank will receive only a single impression in conformity with the shape of the cams by which the fingers 17 or 18, as the case may be, are held open 85 while the other two fingers are raised after each half revolution of the corresponding shaft so that the blanks will move on after each impression.

In the machine illustrated in Figs. 7, 12, 13, and 14, the cam shaft 25 is provided with a third cam in each gear box, for instance, the cam 22'' in Fig. 7, and this cam is placed in cooperative position with respect to the arms 19', 20', and 21' of the transverse shafts. 90 In addition to the three shafts—the shaft 19 is not shown in Figs. 12 to 14—a fourth shaft 21'' is provided at the rear of the shaft 21, with a finger 18' and rollers 35'. In this machine, the fingers are so controlled as to release the blanks at the finger 16 of shaft 19 only after each third operation of the printing arm 6, and the fingers 17, 18, and 18' are so controlled as shown, that a blank 80 is first arrested by the finger 17, Fig. 12, then by the finger 18, Fig. 13, and finally by the finger 18', Fig. 14. Three impressions are made on the same blank in this manner, and the blank is finally released by the finger 18' after the third impression.

I claim:

1. In a multiform printing press having means for printing a sheet in successive positions, stop fingers for holding the sheet in each position, and means for advancing the sheet from one position to another, means for operating said stop fingers comprising a shaft, means for rotating said shaft, cams on said shaft for operating said stop fingers, and means for alternatively placing said

cams in operative position with respect to said stop fingers.

2. In a multiform printing press having means for printing a sheet in successive positions, stop fingers for holding the sheet in each position, and means for advancing the sheet from one position to another, means for operating said stop fingers comprising a

shaft adapted to be displaced axially, means for rotating said shaft, and cams on said shaft for operating said stop fingers adapted to be placed alternatively into operative position with respect to said fingers by such axial displacement. 10

In testimony whereof I affix my signature.
JOSEPH KRELL.
